FURNACE FOR HEATING MATERIALS UNDER
SUSTAINED PRESSUREPeter R. Church, Steubenville, Ohio, and Henri
C. Rateau, Weirton, W. Va.

Application April 2, 1936, Serial No. 72,346

7 Claims. (Cl. 263—43)

This invention relates broadly to furnaces, and more specifically to furnaces for heating or "soaking" steel ingots preparatory to introduction of the ingots to the blooming mill in the process of manufacturing steel sheets and the like.

5 The primary object of the invention is to provide a furnace of the character described requiring a minimum of floor space in which the ingots are heated under a continuous sustained pressure in such a manner as to create a uniform heating and soaking condition without permitting the impingement of fuel combustion to attack any portion of the metal during the heating and soaking period.

10 Another and important object of the invention is to afford re-circulation of waste heat and gases in the furnace in such a manner that they can be readily induced to mix with the delivery of fuels to the furnace to facilitate efficient combustion. Thus, while the furnace affords a better 15 quality of heating it also can be economically operated by reason of utilizing and re-introducing into the furnace for purposes of complete combustion fuels and gases which would otherwise be wasted.

20 Another object of the invention is to provide a furnace structure which can be economically constructed and operated, and one in which the cost of upkeep is comparatively small. Other objects and advantages of the invention will appear from the following detailed description taken in connection with the accompanying illustrative drawings, in which—

25 Figure 1 is an isometric view of the furnace, portions thereof being cut away and shown in section to illustrate interior construction;

30 Figure 2 is a fragmentary horizontal sectional view taken on line 2—2, Fig. 1;

35 Figure 3 is a top plan view of the furnace with the cover and fans removed;

40 Figure 4 is a vertical sectional view taken on line 4—4, Fig. 3; and—

45 Figure 5 is a fragmentary vertical sectional view of the bottom portion of the furnace taken on line 5—5, Fig. 3.

50 Referring to said drawings, the reference numeral 2 designates a concrete base supporting the furnace structure, the latter consisting of side walls and end walls 3 and 4, respectively. Each of said walls is preferably formed to an appropriate thickness of brick, the outer portion of the wall consisting of common clay or building brick while the inner portion or lining consists of a suitable refractory brick. Located intermediate the common clay brick and the refractory brick lining is

a thickness of an appropriate insulating material 5, the same obviously being provided to reduce the dissipation of heat through the furnace walls.

5 A rectangular inner wall 6 is provided at a spaced distance from the lining of the outer walls 3 and 4 to provide an air space or passage 7 therebetween, the wall 6 being maintained rigid by a plurality of staggered tie bricks 8 anchored to the respective wall structures. A plurality of ports 10 arranged in staggered relation and to a predetermined height in the wall 6 afford means of communication from the interior heating chamber of the furnace to the vertical passages 7.

10 The sub-floor 11 is preferably made of refractory brick with a layer of insulation 12 intermediate predetermined courses of brick, the sub-floor being recessed, as shown at 13, to provide means for accommodating the removable ingot supporting floor which will now be described.

15 A series of spaced parallel ingot supporting ribs 14 extend longitudinally of the furnace bottom, said ribs being made of a substance, as metal having high heat resisting properties. Heat resisting concrete 15, reinforced by rods 16, is provided in the spaces intermediate each rib 14, the concrete being of such depth as to permit the upper portion of each rib to protrude upward above the level of the concrete upon which the ingots 17 are supported in spaced relation, one such ingot being depicted in Figs. 1 and 3 of the drawings.

20 Transverse braces 18, also made of high heat resisting metal, underlie the ribs 14 at a spaced distance from the opposite ends of the latter and are embedded in the concrete 15 and, additionally, have their lower edges snugly received within registering transverse grooves provided in the sub-floor 11. A series of spaced notches 19 cut out of the transverse braces 18 receive the horizontal ribs 14, as shown in Fig.

25 4, for affording rigidity to the latter. From the above description it will be observed that the ingot supporting floor is capable of being removable as a unit from the furnace for repairs or replacement. Otherwise expressed, the ribs 14 and intermediate concrete 15 overlie the braces 18 30 and all of said elements can be removed as a unit merely by elevating the two braces 18. Apertures 20 are provided in each of said braces to accommodate hooks of a lifting crane to facilitate removal.

35 Flues 21 are provided in the end walls 4 adjacent the bottom thereof and on substantially the same plane as the surface of the concrete 15. Each of said flues 21 is in vertical alignment with the passage 7 and is isolated from the latter.

50

55

by a baffle wall 22. Openings 23 are provided in the end walls of the walls 6 at the floor level of the furnace, the openings being arranged so that one thereof is provided between each two 5 ingot supporting ribs 14. Thus, communication between the flues 21 and the heating chamber is provided.

A conductor pipe 24 equipped with a damper 25 extends downwardly and outwardly from each 10 of the opposite ends of the two flues 21, each thereof being appropriately connected to a chimney or stack (not shown) for carrying off products of combustion when the dampers 25 are open.

15 Another tube 26 extends horizontally through each of the end walls 4 adjacent the bottom and at a spaced distance from the four corners of the furnace and has its inner end in open communication with the flue 21, each of said tubes being equipped with a damper 27. The outer end of each tube 26 protruding exteriorly of the end walls of the furnace is turned upwardly and is connected with a fan 28, which latter is, in turn, connected to a smaller tube 29 penetrating the furnace end walls and opening into the heating chamber in alignment with the burner opening 30 of the end walls of the inner wall 6.

Similar burner openings 30 are provided in 30 each of the side and end walls of the inner wall 6 adjacent the upper end thereof, the same being intended to register with burners 31 entering through the outer wall and supplied with fuel, as gas, oil, powdered coal, or the like. While a burner 31 and burner opening 30 is herein shown in relation with each side and end wall, it will be understood that the number and location may be varied. The burner depicted in section in Fig. 1 of the drawings is adapted to utilize air 40 and gas as fuel, the air being supplied under a predetermined velocity through the outer tube 31, while the gas is supplied through the inner and smaller tube 32.

45 A number of clean-out openings 33 are provided in the end of the furnace, these openings preferably being located in register with the flue openings 21 and affording means whereby the furnace floor may be appropriately cleaned of undesirable foreign matter from the exterior at 50 intervals by the insertion of an appropriate implement. Removable closures, as 34, seal said clean-out openings 33 when the latter are not being utilized.

55 A removable cover 35 closes the top of the furnace, the same being lined with a heat resisting material. Peep holes (not shown) may, if so desired, be provided in said cover 35 through which the interior of the furnace may be viewed during operation, the peep holes being closed 60 when not in use.

65 In operation, a plurality of ingots, as 17, are placed in the furnace through the opening in the top and are arranged in spaced vertical position with their lower ends resting upon the ribs 14, after which the cover 35 is positioned for sealing the heating chamber from the atmosphere. Fuel is introduced into the heating chamber through the burners 31 and, when ignited, the products of combustion raise the temperature and pressure 70 of the heating chamber to the desired point, the fuel thereafter being permitted to complete its combustion under a continuous and sustained pressure condition. Waste heat and gases, due to the sustained pressure maintained in the heating chamber, are permitted to course through the

ports 10 into the vertical passage 7 from whence they are forced or drawn toward the burner openings 30 and are permitted and induced to commingle with the fuel delivered through the burners 31 after which substantially complete 5 combustion and utilization of the otherwise waste heat and gases takes place within the heating chamber.

Since the heating chamber is under predetermined sustained pressure, varying pressure or 10 temperature zones or pockets are eliminated, and, consequently, the temperature thereof is maintained uniform throughout and the ingots are, therefore, uniformly heated. Moreover, continuous circulation of the products of combustion 15 is experienced permitting the lower portions of the ingots to be heated equally with the top portions. Since the ingots are supported on the upstanding spaced ribs 14, the heating temperature has access to the very bottom of each ingot 20 inasmuch as circulation thereunder is afforded.

The meeting of the air and gas at the burner, as well as the pressure maintained in the heating chamber, acts to reduce the velocity of the 25 delivered fuel so that the objectionable rashness of the heat so injurious to metals is materially reduced, if not entirely eliminated. Furthermore, impingement of fuel combustion on the ingots is further eliminated by preferably 30 placing the burners 31 at a point above the plane of the ingots, although, as hereinbefore stated, the location of the burners may be varied. Experience also teaches that for quality heating the ingots should not be placed in direct line with 35 the line of fire of the burners.

Waste products of combustion may be removed from the furnace by opening the dampers 25 thereby permitting the waste products to course along the floor between the ribs 14 and make 40 their exit from the heating chamber to the flues 21 through the openings 23. From the flues 21 the waste products are carried to the chimney through the conductors 24. This precise method may also be resorted to when it is desired to decrease or otherwise control the pressure maintained within the heating chamber.

On the other hand, it may be found advantageous during the operation of the furnace to close the dampers 25; open the dampers 27 and 50 operate the fans 28 to re-introduce the heated waste products of combustion into the furnace under pressure to mix with the delivered fuel in order to secure maximum combustion. Then, too, as is well known in the art, the furnace may 55 be even more efficiently and economically operated by suitably preheating the fuels prior to introduction into the furnace.

Moreover, the intensity, velocity, volume and direction of the fuel firing burners may be so 60 regulated and positioned as to control the thickness of the scale formed on the ingots during treatment, it being desirable in some cases to have heavier layers of scale than in other instances.

While we have herein described and illustrated a preferred embodiment of the invention, and described the same as being utilized for the purpose of heating steel ingots, it will be apparent that various changes and alterations might be made 70 in the described and depicted structure so that the furnace might readily be adapted for heating materials consisting of other composition of matter. Moreover, we do not desire to be restricted to any limited temperature by the word 75

"heating" as used herein and hereafter. Hence, it is not intended to be limited to the precise details set forth, and we shall consider ourselves at liberty to make such changes and alterations as fairly fall within the spirit and scope of the appended claims.

What is claimed is—

1. In a furnace for heating materials under sustained pressure consisting of outer side and end walls and a removable closure for the charging opening, an inner heat chamber defining wall spaced away from said outer side and end walls to provide a passageway therebetween, a burner penetrating the outer wall and in register with an opening in the inner heat chamber defining wall, a plurality of ports provided in the heat chamber wall affording an avenue for the passage of products of combustion from the heating chamber to said first mentioned passageway and thence to said burner opening from whence said products of combustion may be re-introduced to the heating chamber through the burner opening in the heat chamber wall along with the fuel.
2. In a furnace for heating materials under sustained pressure, an outer wall, a closure, an inner wall defining a heating chamber, said inner wall being spaced away from said outer wall to provide a passageway therebetween, a burner penetrating the outer wall and in register with an opening in the inner heat chamber defining wall, a plurality of ports provided in the lower portion of the heat chamber wall affording an avenue for the passage of products of combustion from the heating chamber to the passageway and thence to said burner opening from whence said products of combustion may be reintroduced to the heating chamber through the burner opening in the heat chamber wall along with the fuel, and a flue beneath and isolated from said passageway and communicating with the heating chamber and leading exteriorly of the furnace whereby products of combustion may be emitted from the furnace.
3. In a furnace for heating materials under sustained pressure, outer side and end walls, a removable closure for the charging opening, an inner heat chamber defining wall spaced away from said outer side and end walls, a burner penetrating the outer wall and in register with an opening in the inner heat chamber defining wall, said opening communicating with the heating chamber and the space between the heating chamber wall and the outer walls, a plurality of ports provided in the lower portion of the heat chamber wall and extending throughout the horizontal extent thereof affording avenues for the passage of products of combustion from the heating chamber to the space between the heating chamber wall and the outer walls from whence they may be conducted to said burner opening for reintroduction to the heating chamber through said opening along with the fuel introduced from the burner.
4. In a furnace for heating materials under sustained pressure consisting of outer side and end walls and a removable closure for the charg-
- ing opening, an inner heat chamber defined by side and end walls spaced away from said outer walls to provide a passageway between the inner and outer walls encompassing said heat chamber, means for introducing fuel to said heating chamber through an opening in the heating chamber wall, and avenues of communication between said heating chamber and the encompassing passageway provided in said heating chamber walls affording avenues for the passage of products of combustion from the heating chamber to said passageway and thence to said burner opening from whence said products of combustion may be re-introduced to the heating chamber through the burner opening in the heat chamber wall along with the fuel.
5. In a furnace for heating materials consisting of outer walls and inner heat chamber defining walls spaced away from said outer walls to provide a passageway therebetween, a burner penetrating the outer wall and in register with an opening in the inner heat chamber defining wall, ports provided in the heat chamber walls affording an avenue for the passage of products of combustion from the heating chamber to said first mentioned passageway and thence to said burner opening from whence said products of combustion may be re-introduced to the heating chamber through the burner opening in the heat chamber wall along with the fuel.
6. In a furnace for heating materials, an outer wall, oppositely disposed walls confined within and spaced away from said outer wall to define a heating chamber and providing a passageway between said heating chamber walls and said outer wall, means for introducing fuel to said heating chamber through an opening communicating with the heating chamber and said passageway, and avenues of communication between said heating chamber and the passageway provided in the heating chamber walls whereby products of combustion from said heating chamber may enter said passageway through opposite heat chamber walls and course through said passageway to said fuel opening from whence they may be re-introduced to the heating chamber through said fuel opening along with the fuel.
7. In a furnace for heating materials, an outer wall, oppositely disposed walls confined within and spaced away from said outer wall to define a heating chamber and providing a passageway between said heating chamber walls and said outer wall, means for introducing fuel to said heating chamber through an opening communicating with the heating chamber and said passageway, and an avenue of communication between said heating chamber and the passageway provided in said heating chamber wall whereby products of combustion may enter said passageway from the heating chamber and be conducted to said fuel opening while confined within the outer wall whence they may be re-introduced to said heating chamber through said fuel opening along with the fuel.
